UNITED STATES PATENT OFFICE.

STACY SHOWN AND WILLIAM B. SMITH, OF SEATTLE, WASHINGTON.

DESIGN FOR A FINGER-RING.

No. 40,050.

Specification for Design.

Patented June 15, 1909.

Application filed January 21, 1909. Serial No. 473,583. Term of patent 7 years.

To all whom it may concern:

Be it known that we, STACY SHOWN and WILLIAM B. SMITH, citizens of the United States, and residents of the city of Seattle, in the county of King and State of Washington, have invented a new, original, and ornamental Design for Finger-Rings, of which the following is a specification, reference being had to the accompanying drawing, forming a part thereof.

Figure 1 is an edge view or elevation of the

ring. Fig. 2 is a face or circular view of the ring. Fig. 3 is a view of similar character to Fig. 1 but taken from the opposite side.

We claim:

The ornamental design for a finger ring, as shown.
